DESIGN FOR A WEDDING RING

Louis Beitchman and Aaron Hechtman,
Brooklyn, N. Y.

Application February 9, 1938, Serial No. 74,996

Term of patent 3½ years

To all whom it may concern:

Be it known that we, Louis Beitchman and Aaron Hechtman, citizens of the United States and residents of the Borough of Brooklyn, in the city and State of New York, have invented a new, original, and ornamental Design for a Wedding Ring, of which the following is a specification, reference being had to the accompanying drawing, forming a part thereof.

Fig. 1 represents a perspective view of a wedding ring showing our new design, and

Fig. 2 represents a developed plan view of the same.

We claim:

The ornamental design for a wedding ring substantially as shown.

LOUIS BEITCHMAN.
AARON HECHTMAN.
